(57) **CLAIM**

The ornamental design for a side cutter for bucket, as shown and described.

DESCRIPTION

FIG. 1 is a front elevational view of the side cutter for bucket showing my new design;

FIG. 2 is a rear elevational view of the present invention;

FIG. 3 is a right side view of the present invention;

FIG. 4 is a left side view of the present invention;

FIG. 5 is a top plan view of the present invention;

FIG. 6 is a bottom plan view of the present invention; and,

FIG. 7 is a reference drawing showing the present invention in a use situation.

The broken line showing of the excavator bucket is included for the purpose of illustrating environment only and forms no part of the claimed design.
